WIRE CABLE OR ROPE

Norman Stanley Ellis, Hamilton, Ontario, Canada, assignor to Metal Textile Corporation, West Orange, N. J., a corporation of Delaware

Application July 1, 1941, Serial No. 400,618

4 Claims. (Cl. 57—145)

This invention relates to improvements in wire cable or rope; and the invention has reference, more particularly, to a novel center member or core around which the convolved wire strands of the cable or rope are laid.

In the production of wire cable or rope it has heretofore been the usual practice to provide a center member or core comprising roped fibrous material, such as sisal, hemp, jute or similar vegetable fibre. Center members or cores of such fibrous material are subject to comparatively rapid deterioration, which results in a breaking down of the required supporting and cushioning effect, whereby relative displacement of the convolved wire strands of the cable or rope occurs, with consequent increased risk of "nicking" and ultimate parting or breaking of said strands, thus greatly reducing the useful life of the cable or rope. Furthermore, such center members or cores of fibrous material have little or no capacity for holding a lubricating substance, and, in fact, are likely to be deleteriously affected by lubricants.

Having in view the above stated objections, and other objections not more particularly enumerated, which use of center members or cores of fibrous vegetable or like material involve, it is an object of this invention to provide a center member or core of novel structure and material which is not only calculated to avoid said objections but is further calculated to provide advantages not obtainable by use of a center or core made of vegetable or other fibrous material, viz., a greater degree of longitudinal pliability without substantial cross-sectional deformation or loss of compressibility; a stronger and more uniform supporting and cushioning effect; a greater capacity for holding lubricating substance coupled with high resistance to any deleterious effects due to the presence of such lubricating substance; as well as other advantages, not at this time more particularly enumerated, but which will be understood from the following detailed description of this invention. To such ends, the novel center member or core for wire cable or rope according to this invention comprises, a metallic mesh fabric made of knitted wire, said fabric being transversely rolled, roven or otherwise formed into a pliable rope-like body which possesses a suitable degree of transverse compressibility for cushioning effect while nevertheless providing a strong and uniform supporting effect, and whereby a body of interstitial or foraminous internal structure is provided capable of being charged with and having a substan-

tial capacity for holding a suitable lubricating substance.

An illustrative embodiment of this invention is shown in the accompanying drawing, in which:

Fig. 1 is a side elevation of a portion of wire cable or rope according to this invention, certain of the convolved wire strands being spread apart to disclose the novel center member or core, and an end portion of the latter being likewise spread apart to show the knitted character of the metallic mesh fabric of which it is composed; and Fig. 2 is a transverse sectional view of the cable or rope drawn on an enlarged scale.

Referring to the drawing, the reference character 10 indicates the novel center member or core. Said center member or core 10 is produced from a strip or strips of knitted metallic wire fabric 11 of suitable width. The strip or strips 11 optionally comprise flat or warp knit fabric or tubular knit fabric. Said strip or strips 11 are laterally and more or less tightly rolled, roven or otherwise manipulated to form the compact but pliant rope-like body 10 of the center member or core. Said strip or strips being laterally rolled, roven or similarly manipulated, the knitted loops are disposed parallel to the longitudinal axis of the resultant body 10, thus permitting relative longitudinal sliding action of adjoining interknit loops. Owing to such permissible longitudinal sliding play or telescopic action between the interlinked loops in either direction, the center member or core body, when flexed, will react to longitudinal stretch in the outer areas of its curvature and will be subject to longitudinal compression or contraction in the inner areas of its curvature. It will be obvious that these different and opposite relative sliding movements of interlinked knit loops in the outer and inner areas of a flexed and curved section of the center member or core body 10 will be mutually compensating, and the longitudinal flexing of the body 10 will not result in any substantial alteration of cross-sectional shape and area thereof, nor will wrinkling or bulging occur along the inner areas of the bent body. Due to such compensating longitudinal expansion and contraction, the supporting and cushioning effect of the center member or core relative to the convolved wire strands 12, which are laid upon and about said center member or core, will be substantially uniformly maintained, throughout the length or run of the cable or rope, with respect to both straight and flexed or curved portions or courses of the cable or rope, when the latter is in use.

In the complete cable or rope, a plurality of wire strands 12, each composed of a plurality of convoluted wires in the usual manner, are convolutedly laid upon and around the center member or core body 10 pursuant to conventional cable or rope manufacturing methods. As shown, the cable or rope embodies six wire strands 12, but it will be obvious that a greater or less number of such strands may be employed, or instead of employing wire strands each composed of a plurality of convoluted wires, a plurality of individual wires may be laid upon and around the center member or core body 10, all as well known in the cable or rope manufacturing industry.

The novel center member or core body 10, as composed of knitted metallic mesh and characterized as above set forth, not only possesses great flexibility or pliancy but also a nicely balanced degree of compressibility so that it will readily conform itself to the wire strands 12 laid upon and about the same so as to provide adequate support for said strands and desired cushioning thereof, and yet will not be so soft or deformable as to permit undue relative displacement of the strands with risk of "nicking" of the wires or kinking thereof likely to weaken and subject the same to the further risk of breaking.

One of the marked advantages of the novel center member or core according to this invention is that the pliant rope-like body thereof, due to its formation from knitted metallic mesh, is of an interstitial or foraminous structure, whereby the same may be readily impregnated with a suitable lubricating substance, such e. g. as graphite; and since this interstitial or foraminous structure is substantially uniform throughout the mass of the center member or core body, the latter possesses a considerable lubricant holding capacity. The provision of such lubricant holding capacity is of great advantage, since exudation of the lubricant from the center member or core body 10 to the contacting surfaces of the laid wire strands 12, and to those of the individual wires of which said strands are composed, reduces friction between said surfaces, thus not only preserving the same from wear, but also adding considerably to the pliancy of the cable or rope as a whole, when the latter is subjected to the stresses and strains incidental to use thereof. As a result of this the useful life of the cable

or rope is considerably extended, since it is capable of much longer resistance to wear and tear.

It will be understood that the novel center member or core according to this invention may be employed in various styles of wire cable or rope having any desired fabrication or arrangement of its wire elements or strands. It is therefore intended that all matter contained in the foregoing description or shown in the accompanying drawing shall be interpreted as illustrative and not in a limiting sense.

I claim:

1. In wire cable or rope, a pliant foraminous axial core which is elastically compressible laterally, comprising a knitted metallic mesh fabric formed into a rope-like body mass, and wire strands laid upon and about said core so as to be supported and cushioned thereby.

2. In a wire cable or rope, a pliant axial core comprising a knitted metallic mesh fabric formed to provide a foraminous rope-like body mass which is elastically compressible laterally, said foraminous body mass being impregnated with a lubricating substance, and wire strands laid upon and about said core so as to be supported and cushioned thereby.

3. In a wire cable or rope, a pliant axial core comprising a knitted metallic mesh fabric arranged in laterally convoluted superposed layers to form a foraminous rope-like body which is elastically compressible laterally, wherein the interengaged knit loops of the fabric lie parallel to the axis of the core so that sliding play is permitted between longitudinally adjoined loops toward and from each other throughout the body thereof, and wire strands laid upon and about said core so as to be supported and cushioned thereby.

4. In a wire cable or rope, a pliant axial core comprising a knitted metallic mesh fabric arranged in laterally convoluted superposed layers to form a foraminous rope-like body which is elastically compressible laterally, wherein the interengaged knit loops of the fabric lie parallel to the axis of the core so that sliding play is permitted between longitudinally adjoining loops toward and from each other throughout the body mass thereof, said foraminous body being impregnated with a lubricating substance, and wire strands laid upon and about said core so as to be supported and cushioned thereby.

NORMAN STANLEY ELLIS.
